STAPLER

Sven Svenson, San Francisco, Calif.

Application October 12, 1936, Serial No. 105,285

4 Claims. (Cl. 1—2.2)

My invention relates to stapling machines primarily of the type in which sections are severed from a continuous coil of wire and are formed and inserted into a plurality of sheets to be stapled together and are then crimped in position. A representative stapler of this type is shown in Patent No. 1,897,625.

An object of my invention is in general to improve stapling machines.

10 Another object of my invention is to facilitate the ease of operation of a stapling machine.

An additional object of my invention is to provide a stapling machine in which the reels of stapling wire are readily changed.

15 Another object of my invention is to provide an improved wire clutching means.

An additional object of my invention is to provide an improved wire severing means.

20 A still further object of my invention is to provide improved wire threading means.

The foregoing and other objects of my invention are attained in the embodiment illustrated in the drawings, in which:

25 Fig. 1 is a side elevation with many parts in cross-section on a vertical, longitudinal plane, of an improved stapler in accordance with my invention;

Fig. 2 is a view similar to Fig. 1 but showing the stapler in a different position of operation;

30 Fig. 3 is a bottom plan view of the stapler shown in Fig. 1;

Fig. 4 is a cross-section the planes of which are indicated by the lines 4—4 of Fig. 1;

Fig. 5 is a cross-section the planes of which are indicated by the lines 5—5 of Fig. 1;

Fig. 6 is a cross-section the principal plane of which is indicated by the line 6—6 of Fig. 2;

Fig. 7 is a cross-section of an improved form of wire clutch, the plane of section being indicated by the line 7—7 of Fig. 8;

Fig. 8 is a cross-section the plane of which is indicated by the line 8—8 of Fig. 7;

Fig. 9 is a side elevation of a part of a stapler, showing an improved form of wire reel mounted thereon, the reel being generally illustrated in cross-section the plane of which is vertical and central.

35 In its preferred form, the improved stapler of my invention includes an internally discharging wire reel pivotally mounted on the stapler and feeding wire through a pair of improved wire clutches both of which, together with the stapling head, can be held in a loading position, the wire then passing adjacent a wire cutter which is separate from the stapling hammer, so that the wire

severing operation transpires prior to the forming operation—all to the general purpose of improving materially the ease of operation, facility of loading, and quality of staple provided by the machine.

40 As shown in Figs. 1 to 8 inclusive, the stapler includes a base 6, which preferably is an inverted cup-like metal stamping, having supporting buttons 7 affixed thereto. The base 6 is formed with a pair of upstanding ears 8 through which a pivot pin 9 passes. Pivotally mounted on the pivot pin 9 is a stapling head 11, normally retained in an upper position by a coil spring 12 one end of which engages a downturned lug 13 projecting from the base 6, and the other end of which engages a lever 14 forming part of the stapling head 11 and when in upper position contacting the base 6 to provide a stop.

45 Pivottally mounted on the stapling head 11 is an actuating lever 16 having a pair of ears 17 encompassing a pivot pin 18 which passes through projections 19 forming part of the stapling head. A hand button 21 at the extremity of the lever 16 provides a convenient means for actuation of the lever, which is ordinarily urged into uppermost position by a relatively powerful coil spring 22 at its lower end resting on a bridge 23 spanning the stapler head 11 and at its upper end abutting against a button 24 extending from the lever 16.

50 On the rearward portion of the stapling head 11 is mounted a removable casing 28 containing a spool of staple wire which extends from the casing through a wire clutch 29 fast on the stapling head 11. The wire clutch is of a sort to permit passage of the wire in one direction but to prevent retrograde movement of the wire.

55 A convenient form of clutch is shown in detail in Figs. 7 and 8. A pair of side plates 31 and 32 are held a convenient distance apart by an upper space block 33 and a lower space plate 34. Rivets 36, suitably spaced, hold the plate in proper position. The plate 34 is separated from the block 33 sufficiently to provide a relatively straight through channel 37 which adjacent its end is enlarged to provide a chamber 38 within which a jamming roller 39 is reciprocable. The roller is carried on an axle 41 passing through clearance apertures 42 in the plates 31 and 32, and received between the forked ends 43 of the parallel levers 44 upstanding from an actuating arm 46. A pivot pin 47, passing through the plates 31 and 32 and the space plate 34 as well as through the levers 44, provides a pivotal mounting, so that when the arm 46 is moved

upwardly against the urgency of a coil spring 48 interposed between the arm and the plates 31 and 32, the jamming roller 39 is moved to a lower part of the chamber 38, freeing the staple wire 51 for forward movement. When the lever 46 is under the influence of the spring 48 alone, it assumes a lower position wherein the roller 39 is in a higher part of the chamber 38 and is in contact with the staple wire 51. In such position, movement of the staple wire to the right in Fig. 7 rotates the roller 39 to the right and into a lower part of the chamber 38, freeing the staple wire 51 for forward movement; whereas retrograde movement, or movement towards the left in Fig. 7, rolls the roller 39 to a shallower part of the chamber 38 and jams the staple wire 51 against the space block 33, preventing any retrograde movement thereof.

The clutch 29, mounted on the stapling head 20 11, therefore permits forward movement of the staple wire 51 but prevents any retrograde movement thereof. A similar clutch 56 is mounted on a reciprocable slide 57, designed for rectilinear translation along the bottom of the stapling head 11. The slide 57 is reciprocated through the medium of a bell crank 58, one arm 59 of which engages a pin 61 on the slide 57, and the other arm 62 of which is engaged by a foot 63 on a vertical slide 64 which is depressed by depressing movement of the button 21 and the lever 16. Thus, when the button 21 is depressed, the slide 64 is lowered, the bell crank 58 is rotated clockwise as seen in Fig. 1, and the slide 57 is translated toward the left in that figure.

Movement of the slide 57 toward the left causes the clutch 56 to ride freely over the staple wire 51 which is prevented from retrogressing by the clutch 29. When the button 21 is released and the lever 16 is urged upwardly by the spring 22, the clutch 57 engages the staple wire 51, the clutch 29 is free to permit forward movement of such wire, and a suitable length of wire is withdrawn from the spool within the casing 28 by the forward movement, or movement toward the right in Fig. 1, of the slide 57.

After a plurality of such operations, the staple wire 51 is fed through an arcuate guide 71 to overlie an anvil 72 formed on the forward part of the slide 57 and to underlie a pair of forming dies 73 and 74 at the lower terminus of the slide 64.

In accordance with my invention, I provide means separate from the dies 73 and 74, for severing a predetermined length of wire from the staple wire 51 to provide a blank wire from which a staple can be made. In the usual stapling machine, the act of severing the wire is concurrent with the initial stages of staple formation, and since the wire is often difficult to cut, this places an excessively high load on the stapling mechanism and makes it difficult to operate during a small part of the operating cycle. I therefore provide a separate cutter, generally designated 81, which comprises a flat plate mounted on a pivot 82 projecting from the stapler head 11. The lower end of the cutter 81 is formed to provide a cutting edge 83 disposed adjacent the terminus of the wire guide 71 and cooperating with a shearing plate 84 on the stapling head 11. To actuate the plate 81 by rotating it around the pivot pin 82, I provide a pin 86 on the slide 64 which engages a continuous cam slot 87 formed in the plate 81, so that, as the slide 64 is depressed due to depression of the lever 16, the pin 86 first rotates the plate 81 clockwise as seen

in Fig. 1, and lowers the cutting edge 83 to sever a length of staple wire. Subsequent downward movement of the slide 64 restores the slide 81 by an anti-clockwise rotation as seen in Fig. 1, to its uppermost or non-cutting position. The shape of the slot 87 is such that it affords greatly increased leverage over that normally possible for severing of the wire, so that the initial downward movement of the lever 16 is effective to sever the wire with a great mechanical advantage, thereby reducing materially the load on the operating lever 16 and facilitating greatly the ease of operation of the structure.

The subsequent formation of the staple which occurs during further descending movement of the dies 73 and 74 and after a wire blank is severed by the edge 83, is in accordance with standard practice and is not described, therefore, in detail.

In order to facilitate the loading of the stapling machine when the wire in one wire reel is exhausted and it is necessary to utilize another reel, the casing 28 is changed and a subsequent staple wire 51 must be threaded through the clutches 29 and 56 successively. This has heretofore been accomplished by the use of auxiliary tools, such as tweezers and the like, and is a difficult, time-consuming and annoying operation. I preferably provide means for holding the structure in a position so that the clutches 29 and 56 are virtually in abutting alignment and the stapling wire 51 can be fed therethrough from one to the other without possibility of intermediate buckling and without the necessity of utilizing any auxiliary tools. For this purpose I mount on the pivot pin 9 a pair of ears 91 projecting from a latch lever 92 which preferably is a metal stamping having a thumb piece 93 at one end and upstruck and provided with a hook 94 at the other end. The latch lever 92 passes through a suitable aperture 96 in the base 6 and can conveniently be provided with an auxiliary thumb piece 97 passing through an aperture 98 in the base. Ordinarily, the latch lever 92 is urged into inactive position, as shown in Fig. 1, by a leaf spring 99 bearing against the lower face of the base 6 and held to the latch lever by a rivet 101 which likewise holds the auxiliary thumb piece 97 in place.

To co-operate with the hook 94, the slide 57 is preferably formed with an undercut depression 102 therein, so that, when the lever 16 is depressed into lowermost location, the thumb piece 93 can be lowered or the thumb piece 97 can be depressed, lifting the hook 94 to enter into the depression 102. When the lever 16 is then released, the urgency of the spring 22 causes the slide 57 to translate toward the right, as seen in Fig. 2, and tightly to engage the hook 94, so that further upward movement of the lever 16 is precluded and so that the clutches 29 and 56 are held in aligned, virtually abutting relationship, with the channel 37 in each forming almost a continuous passage.

While the staple wire can then be threaded into one end of the passage 37 in the rearmost clutch 29 and then forwardly over the rollers 39 in the successive clutches, I prefer to facilitate the operation further by mechanically releasing the rollers 39. This is preferably effected by a projection 111 on the latch lever 92 which engages the lever 46 on the clutch 29, and a projection 112 also on the latch lever 92 which engages the lever 46 on the clutch 56, and by moving them upwardly against the urgency of their springs 47 releases the rollers 39 and provides a free passage entirely

therethrough for the entering staple wire. As soon as the wire has been passed by the operator's hand completely through the clutches 29 and 56, the lever 16 is again depressed slightly so that 5 the hook 94 can disengage itself from the depression 102 under the urgency of the leaf spring 93, thereby simultaneously releasing the clutches 29 and 56, respectively, to assume their wire-engaging position and permitting the springs 22 to force 10 the arm 16 into its uppermost position. The new staple wire is then in position for further feeding, and a plurality of successive operations of the finger button 21 is effective to continue feeding the new wire into the machine. This operation is 15 effected entirely without the use of auxiliary tools, and, since the two clutches 29 and 56 are both mechanically released and held in threading position, the new staple wire 51 can quite readily be inserted therein by a simple maneuver of the operator's fingers.

In order further to facilitate the ease of loading the stapler, and also to provide an increased capacity of staple wire and to prevent undue kinking or tangling of the staple wire, I provide, as shown 20 in Fig. 9, a special improved mounting for the wire reel. In this modification, the pivot pin 18 carries a pair of ears 121 upstanding from a bracket 122 which is enlarged to provide a base plate 123 for a spool casing and which in its 25 lowermost position rests on brackets 124 projecting from the rear of the stapling head 11. Mounted on the base 123 is a central spindle 126, having an enlarged hub 127 on the base thereof, for guiding and receiving a central sleeve 128 forming 30 part of a spool jacket 129. This preferably is of light metal and includes a cylindrical wall 131 and an annular bottom wall 132 to provide an enclosure for a plurality of wire coils 133 which are so wound that they are spaced from the tube 128 35 and are withdrawn from the interior surface, as indicated in Fig. 9. Since the wire 51 is withdrawn from the interior surface, it comes away freely from the layers adjacent and does not tend to pull into the adjacent layers and to tighten or kink. Because of the freedom from tightening 40 and kinking, it is possible to provide at least double the amount of staple wire in a single spool than has heretofore been deemed feasible. The spool is freely rotatable on the spindle 126, so 45 that the wire 51 can be fed through an aperture 141 in the base 123, being either threaded therethrough or brought in from the side through a communicating slot 142. A protection for the spool is provided by an outer cup-like casing 143, held in abutment with the base 123 by a tap nut 144 threaded onto the spindle 126. Whenever it 50 is necessary to renew the spool, the tap nut 144 is removed, the casing 143 is withdrawn, and the empty spool is lifted from the spindle 126. A 55 fresh spool is dropped over the spindle 126, the wire is threaded through the aperture 141, the casing 143 and the tap nut 144 are replaced, and the wire 51 is ready for threading into the clutches 29 and 56 as previously described.

To make somewhat easier the movement of the wire from the aperture 141 into the clutch 29, I 60 preferably move the assembled spool and casing about the pivot pin 18. The base 123 is readily

lifted, and as it is lifted the member 122 passes over a button 151 struck up in one of the side plates of the stapling head 11 and is held frictionally above the button 151 so that the bottom of the base 123 can readily be seen and so that the wire 51 can readily be withdrawn through the aperture 141 and threaded into the rearmost clutch 29. After the wire has been so threaded, the base 123 is pushed downwardly over the frictional retaining button 151 and drops gravitally 10 into place on the bracket 124.

In accordance with my invention, therefore, I have provided an improved stapling machine in which the staple wire is removed from the inside of a reel rather than from the outside thereof; in which a greater quantity of staple wire is provided; in which changing of the reels of wire is greatly facilitated; in which threading of the wire into the stapling machine is made considerably easier and can be accomplished without the use of auxiliary tools, since the stapling head is latched in a threading position; and in which the severing of a predetermined length of wire to provide a staple is effected by a separate cutter so that a suddenly increased load 20 on the actuating lever is obviated and the cutting strain is distributed over a longer period of time thereby greatly facilitating the stapling operation. At the same time, the standard construction of the stapler has not been materially 25 interfered with or altered, so that manufacturing costs are not materially changed and so that the general principle of the machine is maintained.

I claim:

1. A stapling machine comprising a pair of wire-gripping clutches, means for moving said clutches relative to each other between an adjacent position and a remote position, a spring, and means including a manually operable latch for holding said clutches in adjacent position 30 against the urgency of said spring.

2. A stapling machine comprising a stapling head, a wire-gripping clutch on said head, a second wire-gripping clutch on said head, a spring, means for moving said second clutch against the urgency of said spring into a position in approximate abutment with said first clutch, and means for latching said second clutch in said position.

3. A machine comprising a wire-gripping clutch including a pair of side plates, a space block and a space plate interposed therebetween to provide intermediate walls defining a channel having an enlarged chamber, the walls of said chamber and said channel formed by said space plate merging substantially at right angles, a jamming roller in said chamber, and a spring-pressed releasing lever pivotally mounted upon said side plates and engaging said roller.

4. A stapling machine comprising a stapling head, a wire-feeding clutch, a bracket for supporting a coil of stapling wire, and means for pivotally mounting said bracket upon said head for bodily movement with respect thereto in the direction of a wire extending between said clutch and said coil and away from said wire-feeding clutch.

SVEN SVENSON.
